UNITED STATES PATENT OFFICE

2,456,939

WHEELED CONCRETE BURIAL VAULT

Wilbert W. Haase, Forest Park, Ill., assignor
to Wilbert Manufacturers Association, Forest
Park, Ill., a corporation of Illinois

Application September 15, 1945, Serial No. 616,626

4 Claims. (Cl. 280—48)

1

This invention relates to a concrete burial vault.

It has been a customary practice heretofore to deliver concrete burial vaults by truck to some convenient point in a cemetery, which is accessible to the delivery truck, and then to transport the vault across the cemetery sod on rollers to a point adjacent the grave opening. This practice is objectionable for a number of reasons and among these is the fact that the transportation of such concrete burial vaults on rollers across the sod of a cemetery tends to cut furrows in the sod and thus mars the appearance of the cemetery, especially when the ground is soft and wet, as in the spring of the year. Moreover, such concrete vaults are heavy objects and are difficult to move in the manner heretofore employed.

Accordingly, an object of the present invention is to provide a new and improved concrete burial vault which is so constructed and arranged that rubber tired wheels may readily be mounted thereon for transporting the vault from the driveway or other point of discharge from the delivery truck in the cemetery to a point adjacent the grave opening in an easy and expeditious manner and without cutting furrows in the sod of the cemetery or otherwise marring the appearance of the same.

Another object of the invention is to construct the new concrete burial vault in such a manner that the rubber tired wheels may be readily detached from the burial vault at the grave opening.

An additional object of the invention is to provide the new concrete burial vault with a detachable steering device by which the wheel-bearing vault may be readily steered and guided as it is transported across the sod of a cemetery from the point at which it is unloaded from the delivery truck to the grave opening.

Another object of the invention is to provide the new concrete burial vault with a novel device for detachably mounting the steering wheels, embodied in the steering apparatus, upon the body of the vault itself.

Other and further objects of the present invention will be apparent from the following description and claims and are illustrated in the accompanying drawings which, by way of illustration, show preferred embodiments of the invention and the principles thereof and what I now consider to be the best modes in which I have contemplated applying those principles. Other embodiments of the invention embodying the same or equivalent principles may be

2

used and structural changes may be made as desired by those skilled in the art without departing from the present invention and the purview of the appended claims.

5 In the drawings,

Fig. 1 is a side elevational view of a concrete burial vault embodying a preferred form of the present invention;

Fig. 2 is a top plan view of the new concrete 10 burial vault as shown in Fig. 1;

Fig. 3 is a transverse vertical sectional view on line 3—3 in Fig. 1;

Fig. 4 is a fragmentary vertical sectional view 15 on line 4—4 in Fig. 2 illustrating the mounting of the steering apparatus upon the body of the vault; and

Fig. 5 is a side elevational view illustrating a modified form of the invention.

A preferred embodiment of the new concrete 20 burial vault is illustrated in Figs. 1 to 4 inclusive, of the drawings, and is therein generally indicated at 10. The new concrete burial vault 10 comprises a body 11, including side walls 12, a front wall 13, an end wall 14, and a bottom wall 15, the burial vault 10 being shown with the cover removed inasmuch as the cover of the vault does not form a part of the present invention and may be transported separately.

The body 11 of the new concrete burial vault 10 30 may be composed entirely of concrete, or it may be composed of an inner liner of asphalt integrally bonded to an outer layer of concrete.

In molding or otherwise forming the body 11 of the new concrete burial vault 10, I form in 35 the bottom wall 15 thereof two horizontal extending and aligned shaft sockets or openings 16, which may be cylindrical in form, for the reception of wheel-bearing shafts 17. As shown in the drawings the shaft openings 16 extend 40 into the bottom wall 15 from opposite sides thereof. One such pair of shaft sockets or shaft openings 16 is located at a suitable point rearwardly of the center of gravity and rearwardly of the front to rear center of the body 11 of the 45 vault, and another pair of shaft openings or sockets 16 is provided forwardly of the center of gravity and forwardly of the front-to-rear center of the body 11 of the vault. The shaft sockets or openings 16 may be formed in any suitable 50 manner, during the operation of molding or otherwise forming the new burial vault, as by inserting greased dummy shafts or rods into the forms, at the proper points, when pouring or otherwise forming the bottom wall 15 of the 55 body of the vault, allowing such dummy rods or

shafts to remain in position until the concrete has set, and then removing them from the bottom wall 15 of the vault so as to leave the shaft openings or sockets 16.

Each of the rear shaft openings or sockets 16 is adapted to receive and house a cylindrical wheel-bearing shaft 17 on which a rubber tired wheel 19 is mounted and each of the front shaft openings or sockets 16 is adapted to receive and house a similar wheel-bearing shaft 18 on which rubber tired wheels 20 are mounted. Hence, it will be seen that the openings 16 provide bearing openings in which the wheel-bearing shafts 17 and 18 are rotatably but removably journaled.

In order to steer and guide the new concrete vault 10 upon its supporting wheels 19 and 20, I provide a steering or guiding device which is generally indicated at 21 in the drawings. As a part of the guiding or steering device 21 I form a shaft opening or socket 22 in the bottom wall 15 of the vault, during the operation of molding or otherwise forming said bottom wall 15, as by inserting a greased dummy shaft or rod therein during the molding operation and removing the same from the bottom wall 15 after the concrete is set, thus providing the shaft socket or opening 22. As shown in Figs. 2 and 4, the shaft opening or socket 22 is arranged substantially midway between the side walls 12 of the vault and extends rearwardly from the front wall 13 to a point immediately forwardly of the shaft sockets or openings 16 for the front wheel-bearing shafts 18.

The guiding or steering device 21 includes a shaft or rod 23, the rear end portion of which projects into the socket or opening 22 and the front end portion of which extends forwardly of the front wall 13 of the body 11 of the burial vault, as shown. The guiding or steering device 21 also includes a metal plate 24 which includes a substantially triangular shaped front end portion 25 and a depressed or downwardly offset substantially rectangular rear end portion 26. The substantially triangular front end portion 25 of the plate 24 is welded, as at 27, to the shaft or rod 23 and, as shown in the drawings, the substantially rectangular rear end portion 26 of the plate 24 projects under the bottom wall 15 of the body 11 of the burial vault. An angularly extending shoulder portion 28 interconnects the substantially triangular portion 25 and the substantially rectangular portion 26 of the plate 24 and when the plate 24 is in position of use the shoulder 28 abuts the corner formed by the intersection of the front wall 13 and the bottom wall 15 of the body 11 of the vault 10.

The steering or guiding device 21 includes a swivel stud or pin 29 which is mounted in the plate 24, at the front of the substantially triangular portion 25 thereof. A disc or ring 30 is swivelled on the stud or pin 29, above the upper surface of the triangular shaped portion 25 of the plate 24 and a key 31 extended through an opening in the pin or stud 29 keeps these parts in assembled relationship (Fig. 4).

A shaft hanger bracket 37 is formed integral with the disc or ring 30 and this bracket 37 embodies a pair of shaft hanger or bearing arms 32. A shaft 33 is rotatably journaled in bearing openings provided in the shaft hanger arms 32 and a pair of rubber tired pony or guide wheels 34 are mounted on the shaft 33.

Thus it will be seen that the parts 29—30—32—33 and the wheels 34 provide a pony wheel steering or guiding device which is swivelly connected

to the triangular front portion 25 of the plate 24 and that the plate 24 is free to rotate slightly relative to the body 11 of the vault due to the fact that the shaft or rod 23 to which the plate 24 is fastened is journaled in the bearing opening 22 formed in the bottom wall 15 of the body 11 of the vault 10.

To complete the steering or guiding device 21 a handle bar or rod 35 is fastened at its lower end portion, as at 36, upon the bracket 37.

In the use of the new concrete burial vault the wheels 19 and 20 may be installed in position of use either before or after the body 11 of the vault is mounted on the delivery truck for delivery to a cemetery and to a point therein as close as it is possible to reach by delivery truck. This is accomplished by slipping the wheel-bearing shafts 17 and 18 into their respective bearing openings 16 in the bottom wall 15 of the body 11 of the vault, the weight of the body of the vault upon the wheels 19 and 20 maintaining the shafts 17 and 18 in the bearing openings 16.

The pony wheel guiding or steering device 21 may be installed in position of use on the body 11 of the vault 10 by slipping the rear end portion of the shaft 23 into the bearing socket or opening 22, which is formed in the bottom wall 15 of the body 11 of the vault, while at the same time projecting the substantially rectangular rear portion 26 of the plate 24 under the front end portion of the bottom wall 15 of the body of the vault with the offset portion or shoulder 28 abutting the corner formed by the intersection of the bottom wall 15 and front wall 13, as shown in Fig. 4.

After delivery to the cemetery the new concrete burial vault may be moved across the cemetery sod from the point of delivery to a point adjacent the grave opening by manually pushing upon the body 11 of the vault. During this movement the weight of the body 11 of the vault will rest upon and will be distributed over the four rubber tired wheels 19 and 20 so that the sod of the cemetery will not be marred by furrows cut therein. During this operation the wheel-bearing body 11 of the concrete burial vault may be guided by means of the handle bar 35 and attached pony truck 29—30—31—32—34—37. As the body 11 of the vault 10 is thus moved across the cemetery from the point of delivery by truck to the grave opening the shaft 23 is allowed limited turning movement in its socket or opening 22 as the wheels 19 and 20 move over irregularities in the ground or cemetery sod surface.

After the body 11 of the new concrete burial vault has been delivered to a point adjacent the grave opening, the steering or guiding device 21 may be readily detached therefrom by simply pulling the rear end portion of the shaft 23 out of its socket or opening 22 in the bottom wall 15 of the body 11 of the vault 10. The front and rear wheel-bearing shafts 18 and 17 and the wheels 20 and 19, respectively, attached thereto may then be detached from the body 11 of the vault 10 by raising the body 11 of the vault slightly and pulling the wheel-bearing shafts 17 and 18 out of their respective sockets or openings 16, as indicated in dotted lines in Fig. 3.

A modification of the invention is illustrated in Fig. 5, and is therein generally indicated at 10a. This form of the invention is, in general, similar to the form of the invention shown in Figs. 1 to 4, inclusive, and differs therefrom only in the fact that only one pair of supporting wheels 19a is mounted upon the body 11a of the vault, in this form of the invention, rather than two

pairs of the same, as in the form of the invention shown in the Figs. 1 to 4, inclusive.

Hence in the form of the invention shown in Fig. 5, those parts thereof which are otherwise similar to parts embodied in the form of the invention shown in Figs. 1 to 4, inclusive, have been given the same reference numerals, followed by the additional reference character "a."

It will thus be seen from the foregoing description, considered in conjunction with the accompanying drawings, that the present invention provides a new and improved concrete burial vault having the desirable advantages and characteristics, and accomplishing its intended objects, including those hereinbefore pointed out, and others which are inherent in the invention.

I claim:

1. A vehicle of the character described, comprising, in combination, a concrete burial vault comprising a unitary concrete vault body including side walls, a front wall, a rear wall and a bottom wall having two pairs of transversely extending bearing openings formed integrally in the concrete thereof, said transversely extending bearing openings extending inwardly in said bottom wall at substantially right angles to the said side walls of said vault body, the said bottom wall of said vault body having an additional and longitudinally extending bearing opening formed integrally therein and said additional bearing opening extending rearwardly in the said bottom wall of said vault body from the said front wall thereof along a line approximately midway between and substantially parallel to the side walls of said vault body, said additional and longitudinally extending bearing opening in the said bottom wall of said vault body opening at its front end upon the front surface of the front wall of said vault body, each of said two pairs of said transversely extending bearing openings having a wheel-bearing shaft removably journaled therein, said additional and longitudinally extending bearing opening having a supporting shaft removably journaled therein, said burial vault body having a pony wheel steering device mounted on said supporting shaft, said pony wheel steering device including a plate member having a front end portion attached to the said supporting shaft and projecting forwardly of the front wall of the said vault body and having a pair of pony steering wheels swivelly mounted thereon, and the said plate member including a portion projecting under the bottom wall of the said burial vault body.

2. A vehicle of the character described, comprising, in combination, a concrete burial vault comprising a unitary concrete vault body including side walls, a front wall, a rear wall and a bottom wall having transversely extending bearing openings formed integrally in the concrete thereof, said transversely extending bearing openings extending inwardly in said bottom wall at substantially right angles to the said side walls of said vault body, the said bottom wall of said vault body having an additional and longitudinally extending bearing opening formed integrally therein and said additional and longitudinally extending bearing opening extending rearwardly in the said bottom wall of said vault body from the said front wall thereof along a line approximately midway between and substantially parallel to the side walls of said vault body, said

additional and longitudinally extending bearing opening in the said bottom wall of said body opening at its front end upon the front surface of the front wall of said vault body, each of said transversely extending bearing openings having a wheel-bearing shaft removably journaled therein, said additional and longitudinally extending bearing opening having a supporting shaft removably journaled therein, said burial vault body having a pony wheel steering device mounted on said supporting shaft, said steering device including a plate member having a front end portion attached to said supporting shaft and projecting forwardly of the front wall of said vault body and having a pair of pony steering wheels swivelly mounted thereon, and said plate member including a portion projecting under the bottom wall of the said burial vault body.

3. A vehicle of the character defined in claim 2 in which the said bottom wall of the said concrete vault body has a single pair of the said transversely extending bearing openings formed therein and in which the said single pair of transversely extending bearing openings are located rearwardly of the front to rear center of the said vault body.

4. A vehicle of the character defined in claim 2 in which the said plate member includes a main body extending in a substantially horizontal plane and in which the said portion of the said plate member which projects under the said bottom wall of the said vault body extends in a substantially horizontal plane which is offset downwardly below the plane of the body of the said plate member and has the front portion of the bottom wall of the said vault body resting thereon, and in which the said plate member has a shoulder portion formed therein at and by the intersection of the said body of the said plate member and the said downwardly offset portion thereof, and in which the corner portion of the said vault body formed by the intersection of the said bottom wall and the said front wall of the said vault body bears against the said shoulder portion of the said plate member when the said vehicle is in use.
